(57) **CLAIM**

The ornamental design for a toy surfboard, as shown and described.

DESCRIPTION

FIG. 1 is a top rear perspective view of the toy surfboard. FIG. 2 is a top front right perspective view of the toy surfboard of FIG. 1.

FIG. 3 is a top front left perspective view of the toy surfboard of FIG. 1.

FIG. 4 is a top rear left perspective view of the toy surfboard of FIG. 1.

FIG. 5 is a bottom front left perspective view of the toy surfboard of FIG. 1.

FIG. 6 is a bottom rear right perspective view of the toy surfboard of FIG. 1.

FIG. 7 is a bottom rear left perspective view of the toy surfboard of FIG. 1.

FIG. 8 is bottom front left perspective view of the toy surfboard of FIG. 1.

FIG. 9 is a right side view of the toy surfboard of FIG. 1.

FIG. 10 is a left side view of the toy surfboard of FIG. 1.

FIG. 11 is a top view of the toy surfboard of FIG. 1.

FIG. 12 is a bottom view of the toy surfboard of FIG. 1.

FIG. 13 is a rear end view of the toy surfboard of FIG. 1; and,

FIG. 14 is a front end view of the toy surfboard of FIG. 1. The broken lines in FIGS. 1-14 are for illustrative purposes and form no part of the claimed design.
